ABSTRACT

The present application discloses a portable curtain cutter assembly comprising a base and a portable cutter. The base comprises a supporting plate; a side wall; and a slider. The side wall is coupled to the supporting plate and comprises a first groove. The slider is slidably coupled to the side wall through the first groove, wherein the slider comprises a slot. The portable cutter comprises a blade, wherein the blade is capable of being inserted partially into the slot. A method of using the aforementioned portable curtain cutter assembly is also disclosed.

FIG. 1

FIG. 2

FIG. 3

FIG. 4

FIG. 5

FIG. 6

PORTABLE CURTAIN CUTTER ASSEMBLY AND METHOD FOR USING THEREOF

CROSS-REFERENCE TO RELATED APPLICATION

This application claims priority benefit from China Patent Application No. 201810378015.X, filed on Apr. 25, 2018 in the State Intellectual Property Office of the P.R.C., the disclosure of which is incorporated herein by reference in its entirety.

TECHNICAL FIELD OF THE INVENTION

The present application generally relates to a cutter, and more particularly, to a portable curtain cutter assembly and a method for using thereof.

BACKGROUND OF THE INVENTION

Since each house has different curtain size and length, it is hard to mass manufacture certain scale of curtains for every family. Therefore, people generally hand cut the curtain for adjustment to a desired size.

However, the bottom edge of the curtain will be curved since the upper portion is draped when hanging up. For this reason, it is common for consumers to order customized curtains. But it not only increases the costs but creates even more problems if the customized curtain is incompatible with the house due to mismeasurement.

Therefore, a need remains for a portable curtain cutter assembly and a method for using thereof to provide an improved qualify of curtain to meet the demand of each different house.

SUMMARY OF THE INVENTION

The present application discloses a portable curtain cutter assembly and a method for using thereof to provide an improved qualify of curtain to meet the demand of each different house.

The portable curtain cutter assembly comprises a base and a portable cutter. The base comprises a supporting plate; a side wall; and a slider. The side wall is coupled to the supporting plate and comprises a first groove. The slider is slidably coupled to the side wall through the first groove, wherein the slider comprises a slot. The portable cutter comprises a blade, wherein the blade is capable of being inserted partially into the slot.

In various exemplary embodiments, the base further comprises a screw and a plurality of holes arranged in a column, the screw is capable of being inserted into the plurality of holes. The screw may be a wing screw.

In various exemplary, embodiments, the side wall comprises a second groove, one end of the slider is coupled to the first groove while another end of the slider is coupled to the second groove.

In various exemplary embodiments, wherein the portable cutter further comprises a case defining an accommodation space, the blade is disposed inside the accommodation space. The portable cutter further comprises a fastener coupled to the case. The fastener comprises a rod; a fixture; a roller; a spring and a connector. The rod is hollow and is coupled to the case. The fixture is coupled to the rod. The roller is coupled to the fixture. The spring partially disposed inside the rod. A diameter of the spring is 0.6 mm. A length of the spring is 30 mm. The connector is disposed inside the

rod and coupled to the spring, wherein the rod and the case are coupled via the spring and the connector.

In various exemplary embodiments, wherein the portable cutter further comprises a case defining an accommodation space, the blade is disposed inside the accommodation space; and a handle coupled to the case and comprising stainless steel.

In various exemplary embodiments, the base further comprises a fixing bar, a first bar, a second bar, a positioning rod and a spring. The fixing bar is disposed on the supporting plate. The first bar is rotatably coupled to the fixing bar. The second bar is coupled to the first bar. The positioning rod is coupled to the fixing bar. The spring is coupled between the positioning rod and the first bar, wherein the first bar is rotated about the fixing bar via the spring and the positioning rod.

A method for using the aforementioned portable curtain cutter assembly is, also disclosed. The method for using the portable curtain cutter assembly comprises: installing the slider into the first groove of the base; inserting the blade 15 partially into the slot of the slide; placing a curtain between the blade and the slider; and moving the curtain along the slot.

In various exemplary embodiments, the step of moving the curtain along the slot comprises moving the curtain horizontally.

In various exemplary embodiments, before placing the curtain between the blade and the slider, the method further comprises draping the curtain.

Based on the above, the present application allows consumers to have customized curtains simply via using the portable curtain cutter assembly at their houses, reducing the risk of having an incompatible-sized curtain due to mismeasurement. In addition, since the present application discloses a method for cutting a draped curtain, the problem of having a curved bottom edge of curtain can be reduced either.

Numerous other advantages and features of the present application will become readily apparent from the following detailed description of disclosed embodiments, from the claims and from the accompanying drawings.

BRIEF DESCRIPTION OF THE DRAWINGS

The objects, features and advantages of the present application will be more readily appreciated upon reference to the following disclosure when considered in conjunction with the accompanying drawings, wherein like reference numerals are used to identify identical components in the various views, and wherein reference numerals with alphabetic characters are utilized to identify additional types, instantiations or variations of a selected component embodiment in the various views, in which:

FIG. 1 is view showing a portable curtain cutter assembly.

FIG. 2 is a front view a base of the portable curtain cutter assembly.

FIG. 3 is a side view of the base of the portable curtain cutter assembly.

FIG. 4 is a bottom view of a fastener of the portable curtain cutter assembly.

FIG. 5 is a view showing a fabric being cut by the portable curtain cutter assembly.

FIG. 6 is a flow chart of a method for using the portable curtain cutter assembly.

DETAILED DESCRIPTION OF DISCLOSED EMBODIMENTS

Reference will now be made in detail to the present representative embodiments of the present application,

examples of which are illustrated in the accompanying drawings. Wherever possible, the same reference numbers are used in the drawings and the description to refer to the same or like parts.

FIG. 1 is view showing a portable curtain cutter assembly 10.

Referring to FIG. 1, the portable curtain cutter assembly 10 comprises a base 100 and a portable curtain cutter 200. The base 100 comprises a supporting plate 110, a side wall 120, a slider 130 and a fixing assembly 140.

The supporting plate 110 is coupled to the side wall 120. Specifically, one edge of the supporting plate 110 is coupled to one end of the side wall 120, making the supporting plate 110 and the side wall 120 to be connected vertically. A top surface of the supporting plate 110 serves as an operating platform for cutting a curtain.

The side wall 120 comprises two grooves 124a/124b. Specifically, both a left side and a right side of the side wall 120 comprise an insert parts which include the grooves 124a/124b, defining an accommodation space for the slider 130.

The slider 130 is slidably coupled to the side wall 120 through both of the grooves 124a/124b. Specifically, a left side and a right side of the slider 130 are capable of being inserted into the grooves 124a/124b respectively. The slider 130 comprises a slot 132.

FIG. 2 is a front view of a base 100 of the portable curtain cutter assembly 10. FIG. 3 is a side view of the base 100 of the portable curtain cutter assembly 10.

As shown in FIGS. 2-3, the base 100 further comprises a screw 140 and a plurality of holes 150 arranged in a column. The screw 140 is capable of being inserted into the holes 150. Specifically, the user can select a specific hole 150 for a desired height for positioning the slider 130. The screw in the present application is a wing screw as an example, but the present application is not limited thereto. In addition, it should be noted that the amount of the holes 150 is not limited either, the amount of holes 150 in FIG. only shows as an example.

Referring to FIGS. 1-3, the fixing assembly 140 comprises a fixing bar 141, a spring 142, a positioning rod 143, a bar 144 and a bar 145. The fixing bar 141 is disposed and fixed on the supporting plate 110. The positioning rod 143 is coupled to the fixing bar 141. The spring 142 is a torsion spring and is installed with the positioning rod 143.

The bar 144 is rotatably coupled to the fixing bar 141. Specifically, the bar 144 can be rotated about the fixing bar 141 via the spring 142 and the positioning rod 143. The spring 142 is capable of being deformed while the bar 144 is rotated along the arrow 400 because the positioning rod 143 fixes one end of the spring 142 is a fixed position. The bar 145 is coupled to the bar 144 vertically.

Therefore, the user may put the curtain in a desired place after rotating the bar 144 and the bar 145 along the arrow 400. Then, rotating the bar 144 and the bar 145 back to the original places for fixing the curtain, allowing the curtain to be disposed in a desired place. The bar 144 in the present application is curved as an example. However, the present application is not limited thereto. In addition, the spring 142, the bar 144 and the bar 145 are molded integrally in the present application only as an example.

FIG. 4 is a bottom view of a fastener 260 of the portable curtain cutter assembly 10.

Referring to FIG. 1 and FIG. 4, The portable curtain cutter 200 comprises a case 210, a blade 220, a cover 230, a pivot 240, a handle 250 and a fastener 260.

The case 210 comprises a mounting space 212 and defines an accommodation space 214. The case 210 in the present application is circular shape as an example, but the present application is not limited thereto.

5 The blade 220 is disposed inside the accommodation space 214. The cover 230 is pivotally coupled to the case 210 via the pivot 240, increasing the safety when the portable curtain cutter 200 is in use. It should be noted that the cover 230 also be coupled to the case 210 by other methods such as working as a lid or being coupled via screw, the present application is not limited thereto.

10 The handle 250 comprises a switch 252 for turning the portable curtain cutter 200 on or off.

15 The fastener 260 is disposed partially inside the mounting space 212 at a top surface of the case 210 for securing the curtain in a desired location. The fastener 260 comprises a rod 262, a fixture 264, a roller 266, a spring 268 and a connector 269.

20 FIG. 4 shows a view of a bottom surface of the rod 262 being partially removed for clear description of the structure of the fastener 260.

25 The roller 266 is coupled to the fixture 264. The fixture 264 is coupled to the rod 262. The rod 262 is coupled to the case 210 through the spring 268 and the connector 269. Specifically, the rod 262 is hollow and the spring 268 is partially disposed inside the rod 262 and the connector 269 is disposed inside the rod 262 and coupled to the spring 268. When pressing the roller 266 toward the case 210, the 30 connector 269 may be pressed by the roller 264, making the spring 268 be compressed. The spring 268 is released after placing the curtain in the desired location, further securing the curtain in the fixed location.

35 A diameter of the spring 268 is 0.6 mm while a length of the spring 268 is 30 mm. However, the present application is not limited thereto, the diameter and the length of the spring 268 can be modified if needed.

40 By the above structure, the curtain may be secured in a desired location after measurement. In addition, the roller 266 may be rolled when moving the curtain, allowing the curtain be maintained in a same height level.

45 FIG. 5 is a view showing a fabric 300 being cut by the portable curtain cutter assembly 10.

Referring to FIG. 5, as an example, the fabric 300 is 50 moved along the arrow 500 while the portable curtain cutter assembly 10 keeping in a same place. By moving the fabric 300, the fabric 300 is cut along the direction of the blade 220 and the slot 132.

55 FIG. 6 is a flow chart of a method for using the portable curtain cutter assembly 10.

Referring to FIG. 1 and FIG. 6, as shown in a first initial step 602, draping the curtain before cutting the curtain by the portable curtain cutter assembly 10.

In addition, as shown in a second initial step 604, installing 60 the slider 130 into the grooves 124a/124b of the base 100. After that, inserting the blade 210 partially into the slot 132 of the slide 130 as shown in step 606.

Referring to step 608, then placing the curtain between the blade 220 and the slider 130. Then moving the curtain along the slot 132 horizontally as shown in step 610.

65 Based on the above, the present application allows consumers to have customized curtains simply via using the portable curtain cutter assembly at their houses, reducing the risk of having an incompatible-sized curtain due to mismeasurement. In addition, since the present application discloses a method for cutting a draped curtain, the problem of having a curved bottom edge of curtain can be reduced.

Meanwhile, since the roller 266 can secure the curtain in the desired location, the curtain can be placed more stable while cutting, further reducing the deviation. Furthermore, the cover may work as a protector to avoid unnecessary harm while using the portable curtain cutter assembly.

It will be apparent to those skilled in the art that various modifications and variations can be made to the structure of the present application without departing from the scope or spirit of the present application. In view of the foregoing, it is intended that the present application cover modifications and variations of this application provided they fall within the scope of the following claims and their equivalents.

What is claimed is:

1. A method for using a portable curtain cutter assembly, wherein the portable curtain cutter assembly comprises:

a base comprising:

a supporting plate;

a side wall coupled to the supporting plate and comprising a first groove; and

a slider slidably coupled to the side wall through the first groove, wherein the slider comprises a slot; and a portable cutter comprising a blade, wherein the blade is capable of being inserted partially into the slot, wherein the method for using the portable curtain cutter assembly comprises:

installing the slider into the first groove of the base; inserting the blade partially into the slot of the slide; placing a curtain between the blade and the slider; and moving the curtain along the slot.

2. The method for using the portable curtain cutter assembly as claimed in claim 1, wherein the step of moving the curtain along the slot comprises moving the curtain horizontally.

3. The method for using the portable curtain cutter assembly of claim 1, wherein before placing the curtain between the blade and the slider, the method further comprises draping the curtain.

4. The method for using the portable curtain cutter assembly as claimed in claim 1, wherein the base further comprises a screw and a plurality of holes arranged in a column, the screw is capable of being inserted into the plurality of holes.

5. The method for using the portable curtain cutter assembly as claimed in claim 4, wherein the screw is a wing screw.

6. The method for using the portable curtain cutter assembly as claimed in claim 1, wherein the side wall comprises a second groove, one end of the slider is coupled to the first groove while another end of the slider is coupled to the second groove.

7. The method for using the portable curtain cutter assembly as claimed in claim 1, wherein the portable cutter further comprises a case defining an accommodation space, the blade is partially located inside the accommodation space.

8. The method for using the portable curtain cutter assembly as claimed in claim 7, wherein the portable cutter further comprises a fastener coupled to the case.

9. The method for using the portable curtain cutter assembly as claimed in claim 7, wherein the fastener comprises:

a rod coupled to the case;

a fixture coupled to the rod; and

a roller coupled to the fixture.

10. The method for using the portable curtain cutter assembly as claimed in claim 9, wherein the rod is hollow and the fastener further comprises:

a spring partially disposed inside the rod; and

a connector disposed inside the rod and coupled to the spring, wherein the rod and the case are coupled via the spring and the connector.

11. The method for using the portable curtain cutter assembly as claimed in claim 10, wherein a diameter of the spring is 0.6 mm.

12. The method for using the portable curtain cutter assembly as claimed in claim 10, wherein a length of the spring is 30 mm.

13. The method for using the portable curtain cutter assembly as claimed in claim 7, wherein the portable cutter further comprises a cover pivotally coupled to the case.
